ELECTRIC SWITCH

Walter Schaelchlin, Wilkinsburg, Pa., assignor to
 Westinghouse Electric & Manufacturing Company, East Pittsburgh, Pa., a corporation of Pennsylvania

Application July 31, 1936, Serial No. 93,577

4 Claims. (Cl. 200—165)

My invention relates to switches, or interrupters, for electric circuits, and more particularly to such switches for controlling sequential operation of electrical apparatus, as motors.

5 One object of my invention is to provide a more reliable, simpler, and less expensive switch for making and interrupting electrical circuits.

Another object of my invention is to eliminate all flexible conductors, or "jumpers" disposed between the movable contact and its terminal now used by prior art devices.

10 A still further object of my invention is the provision of carrying large currents, to be interrupted by switching means, through a pivot disposed between an electric terminal and the movable contact of a switching device energized from such terminal.

15 The usual switch design, of switches generally of the class to which my invention relates, includes a suitable bearing for the moving contact arm and a flexible shunt for carrying the current from the movable contact to its stationary terminal. A switch of this type, representing the prior art, does not offer great difficulties for switches of relatively low current carrying capacities, but become cumbersome, unreliable, and expensive for switches having a large current carrying capacity.

20 A specific object of my invention is a contact arrangement that eliminates both the usual bearing for a movable contact and the flexible shunt disposed between the movable contact and its terminal.

25 One general object of my invention is the provision of switching devices of relatively large current carrying capacities that are simpler, more reliable, and less expensive than the switching devices of the prior art for like capacities.

30 Other objects and advantages will become more apparent from a study of the following specification when considered in conjunction with the accompanying drawing, in which:

Figure 1 is a side view with certain parts in section along a vertical plane;

35 Fig. 2 is a front view of the subject matter shown in Fig. 1; and

Fig. 3 shows a detail of the showings in Figs. 1 and 2.

40 Referring to the drawing and particularly to Fig. 1, the reference character 1 designates the structure upon which control equipment is mounted and upon which my switch designated generally by the reference character 2 is mounted by suitable mounting structures not shown. This 45 switch 2 has a stationary generally shoe-shaped

contact member 3 which is bifurcated to secure better current distribution, particularly during the making and the breaking of the circuit my switch is to control. This stationary bifurcated contact member is provided with a transversely mounted silver strip 4 at its heel and is so mounted as to be somewhat adjustable on the current carrying terminal 5, which adjustment may be effected by the bolt 6 fitting loosely into the current carrying terminal 5. The terminal 5 is 5 rigidly secured to an L-shaped insulating member 7 by the bolts and nuts 8. The outer member 9 of the terminal 5 is provided with a suitable opening for receiving a binding post or other current transmitting connection. 15

Switches of the type to which class my invention generally belong usually have a movable contact member which movable contact member is energized from a stationary terminal. I provide a stationary terminal 10 having the projection 11 for connecting it to the circuit to be controlled. The stationary terminal 10 is rigidly secured to an L-shaped insulating member 12 by means of the bolts and nuts 13. This stationary member has an adjustable current-carrying strip 14, which strip 14 may be adjusted on the terminal 10 by the bolt 15. It will be noted that the bolt 15 passes through a rather large opening in the current carrying strip 14. This current carrying strip may be of silver or may be of any 20 other metal having a large current carrying capacity. Silver, however, usually is the best metal to use, since it insures a low contact resistance in spite of oxidized contact surfaces. 25

If the strip 14 is of copper or some other metal 30 that readily forms an oxide at points where arcs may appear, such strip may be provided with a silver plating at the region where the arcs are to take place or where there may otherwise be heating at the contact regions. The end or region 40 16 where the heating is likely to occur has a rectangular end shape, but may be constructed in the form of a knife edge or arcuate shape to coact with the current carrying strip 17 of one of the movable portions of my switch 2. The member 17 is adapted to oscillate upon the end 16 as a bearing, and if it is necessary that more than a mere line contact should be maintained, the end 16 may be in the form of an arc coacting 45 with a similar recess in the member or movable strip 17 at the end 16. In any case, the amount of current that is to be carried from the current carrying strip 14 to the movable strip 17 will determine the kind of contact, that is, will de- 50

termine the shape of the contact at the end 16 between the strips 14 and 17.

In order that the movable strip 17 may at all times firmly engage the end 16 of the strip 14, an adjustable spring 18 is rigidly connected to the L-shaped insulating members 7 and 12 by the bolt 19 rigidly holding the cylindrical lug 20. The spring 18 is firmly connected to the lug 20 on the insulating member 7 and is similarly connected to a lug 21 threadedly engaging an adjusting stem 22. This adjusting stem 22 passes through an opening in the movable contact strip 17 and has an outer disk portion 23 adapted to engage the outer or arcuate ends of the rivets 24 and 25. Since these rivets are arcuate, the friction at this point will be a minimum and will now in no wise add to the difficulty of operating the movable current carrying strip 17. The pressure with which the movable strip 17 is held against the end 16 will be determined by the adjustment of the spring 18, namely, be determined by the tension to which the spring is subjected by the stem 22. The movable contact carrying strip 17 is also provided with a silver current carrying contact 26 adapted to coact with the silver strip 4 on the heel of the stationary contact member 3.

During normal operation, that is, when all the elements of my switch are in the position shown and the terminals 5 and 10 are connected to a suitable source of energy and the apparatus to be controlled, current will flow through my switch 2 or circuit interrupter from the terminal 5 through the connection between the terminal 5 and the stationary contact member 3, the silver contacts 4 and 26, the movable current carrying strip 17, the end 16 engaging the recess of the movable current carrying strip 17 and the adjustable strip 14 to the terminal 10. From this circuit just traced, it will be apparent that all flexible leads from the terminal 10 to the contact 26 are eliminated and that all of the current during normal operation is carried from the terminal 10 to the movable current carrying strip 17 through the bearing end 16.

My switch may, of course, be actuated in any suitable manner as for instance it might be actuated by an electromagnet. However, in the particular showing I have made the operation of the movable current carrying strip 17 is effected through a cam 27 mounted on a shaft 28 which may be operated either manually or by some pilot motor which is to control the operation of one or a considerable number of switches which control the sequence of operation of a plurality of electrical devices. This cam 27 coacts with a roller 29 mounted on the bifurcated end of the lever 30. This lever 30 carries the rivets 24 and 25 which coact with the disk portion 23 of the stem 22 and is therefore held in the position shown by the spring 18. As the cam 27 is operated the roller 29 will ride upon the upper or outer circumference of the cam and thereby open the circuit between the stationary terminal 3 and the current carrying strip 17. This interruption of the circuit takes place, however, in this manner. It usually is desirable not to subject the terminals or contacts as for instance 4 and 26 normally carrying the current that is to be interrupted to the interrupting arc. To avoid this I provide the movable arcuate member 31 having a knife edge bearing 32 in the movable strip 17. A spring 33 acting upon the arcuate current interrupting member 31 biases this member toward the stationary contact terminal 3 and as the lever

30 rotates in a clockwise direction on the end 16 the arcuate member 31, with reference to the lever 30, rotates in a counter-clockwise direction on its knife edge and therefore provides a shunt for the contact members 4 and 26 after they have separated so that current passes from strip 17 to the bifurcated ends 35 which roll on the stationary terminal 3. The interrupting arc is therefore always carried by the bifurcations 35 of the member 31, and is thus interrupted in substantially the same manner each time the switch is operated. My switch may, of course, be provided with the conventional arc chute and blowout coils which constitute no part of my invention and therefore have not been shown. Whether or not elaborate arc quenching means are used will depend on the currents carried by the switch. Arc quenching devices are usually used with my device and especially when called upon to carry currents as high as 50,000 amperes.

Usually, switches of the type I have shown are used for the purpose of controlling a number of circuits so that a plurality of them are mounted to be operable by the cam 27. Fig. 3 illustrates this to some extent by showing a sectional end view of two of the devices and wherein the section of the upper portion is taken on a device such as shown in Fig. 1, in a plane to illustrate the details of the spring and the adjustable stem more accurately, whereas the section shown in the lower portion of Fig. 3 illustrates the coaction of the stationary terminal 10 with the movable current carrying strip 17 and the bearing end 16.

I am, of course, aware that others, particularly after having had the benefit of the teachings of my invention, may devise industrial circuit interrupters that eliminate the use of flexible leads from the movable contact member to its terminal and I therefore do not wish to be limited to the specific showing made in the drawing nor the specific description hereinbefore given, but my disclosure is to be taken in an illustrative sense and the invention is therefore to be limited only by the scope of the claims hereto appended and such prior art as may be pertinent.

I claim as my invention:

1. In an electric switch, in combination, a first stationary current carrying member, an adjustable contact member carried by said first stationary member and normally rigidly secured thereto, a second stationary current carrying member, an adjustable contact member normally rigidly secured to said second current carrying member, said second contact member having a silvered projecting end designed as a bearing, a movable arm having a recess adapted to receive the second named contact member at the silvered bearing and adapted to be rotatable about said bearing, said movable arm being provided with a contact member at the end not engaging said bearing adapted to cooperate with the adjustable contact member on the first stationary current carrying member, and operating means adapted to move said arm on said bearing portion to make and break, as desired, interconnection between the contact member of the movable arm with the adjustable contact member on the first named current carrying member, said operating means comprising a lever of the first class pivoted at said silvered bearing by virtue of which the contact pressure at said silvered bearing increases as the result of movement of said operating means.

2. In an electric switch, in combination, a

- first stationary current carrying member, an adjustable contact member carried by said first stationary member and normally rigidly secured thereto, a second stationary current carrying member, an adjustable contact member normally rigidly secured to said second current carrying member, said second contact member having a silvered projecting end designed as a bearing, a movable arm having a recess adapted to receive 5 the second named contact member at the silvered bearing and adapted to be rotatable about said bearing, said movable arm being provided with a contact member at the end not engaging said bearing adapted to cooperate with the adjustable 10 contact member on the first stationary current carrying member, operating means adapted to move said arm on said bearing portion to make and break, as desired, interconnection between the contact member of the movable arm with 15 the contact member on the first named current carrying member said operating means comprising a lever of the first class pivoted at said silvered bearing by virtue of which the contact pressure at said silvered bearing increases as the 20 result of movement of said operating means, a bearing recess in said movable arm for receiving a pivotally mounted contact member which pivotally mounted contact member is adapted to temporarily maintain interconnection with the first 25 named contact member after the movable arm is being moved by said operating means.
3. In an electric switch having a pair of stationary contact terminals, one of said terminals being silvered and being designed as a bearing, 30 a movable arm having bearing engagement at one of its ends with the said silvered bearing on one of the terminals, said movable arm having a contact member at the other end, that is, the end remote from the end engaging the bearing, a spring, means for adjusting the tension of the 35 spring, said adjusting means engaging the arm and being disposed to bias the arm against the other of the terminals and against the bearing of the first terminal by a force determined by the adjustment of the adjusting means of the spring, and means comprising a lever of the first class pivoted at said silvered bearing for operating the arm in opposition to the biasing effect of the spring to thus pivotally move the arm on the said bearing with increased bearing contact pressure on one of said contact terminals and away 40 from the other contact terminal.
4. In an electric switch having a pair of stationary contact terminals, one of said terminals being designed as a bearing, a movable arm having bearing engagement with the bearing end 15 of one of the terminals, said movable arm having a contact member at the end remote from the end engaging the bearing adapted to engage the other contact terminal, a tension spring, means for adjusting the tension of the spring, said adjusting means engaging the arm and disposed to bias the arm against the other of the terminals and against the bearing of the first terminal by a force determined by the adjustment of the adjusting means of the spring, operating means for 20 pivotally operating the arm in opposition to the biasing effect of the spring to thus pivotally move the arm on the bearing end of one of the contact terminals and away from the other contact terminal, said arm being provided with a straight 25 recess disposed transversely of the arm, a bifurcated contact member having an edge at one end thereof engaging the base of the recess as a bearing, and a spring for biasing the bifurcated member toward the other contact terminal whereby 30 said contact terminals are not immediately disconnected during the movement of said arm on the bearing surface of the first contact terminal to interrupt the interconnection between the terminals.

WALTER SCHAECHLIN.
